DESIGN FOR A RADIATOR CABINET

Theodore Hess, Prairie View, Ill., assignor to
Modine Manufacturing Company, Racine, Wis.,
a corporation of Wisconsin

Application August 15, 1936, Serial No. 64,427

Term of patent 3½ years

To all whom it may concern:

Be it known that I, Theodore Hess, a citizen of the United States, residing at Prairie View, in the county of Lake and State of Illinois, have invented a new, original, and ornamental Design for a Radiator Cabinet, of which the following is a specification, reference being had to the accompanying drawing, forming a part thereof,

The figure is a perspective view of a radiator cabinet embodying my design, the end of the cabinet not shown being like the end shown in the drawing.

I claim:

The ornamental design for a radiator cabinet, as shown and described.

THEODORE HESS.
